(57) **CLAIM**

The ornamental design for a cross member for fitness device substantially as shown and described.

DESCRIPTION

FIG. 1 is a top, front, right side isometric view of a cross member for fitness device.

FIG. 2 is a bottom, rear, left side isometric view of the cross member for fitness device of FIG. 1.

FIG. 3 is a front elevation view of the cross member for fitness device of FIG. 1.

FIG. 4 is a rear elevation view of the cross member for fitness device of FIG. 1.

FIG. 5 is a left side elevation view of the cross member for fitness device of FIG. 1.

FIG. 6 is a right side elevation view of the cross member for fitness device of FIG. 1.

FIG. 7 is a top plan view of the cross member for fitness device of FIG. 1.

FIG. 8 is a bottom plan view of the cross member for fitness device of FIG. 1; and,

FIG. 9 is a top, front, right side isometric view of the cross member for fitness device of FIG. 1 in an environment of a fitness device.

The broken lines in FIGS. 1-8 illustrate unclaimed features of the design and form no part of the claimed design. The broken lines in FIG. 9 within the bounds of the cross member illustrate unclaimed features of the design and form no part of the claimed design. The additional broken lines in FIG. 9, outside the bounds of the cross member, are for purposes of illustrating use and environment only and form no part of the claimed design.

1 Claim, 6 Drawing Sheets
